UNITED STATES PATENT OFFICE.

JOHN H. LEE, OF MOUNTAIN GROVE, MISSOURI, ASSIGNOR OF ONE-FOURTH TO JOHN W. KEY, OF MOUNTAIN GROVE, MISSOURI.

WIRE-STRETCHER.

No. 835,961.

Specification of Letters Patent.

Patented Nov. 13, 1906.

Application filed March 31, 1906. Serial No. 309,143.

To all whom it may concern:

Be it known that I, JOHN H. LEE, a citizen of the United States, residing at Mountain Grove, in the county of Wright and State of Missouri, have invented a new and useful 5 Wire-Stretcher, of which the following is a specification.

This invention relates to wire-stretchers.

The object of the invention is to improve 10 the construction of such devices; furthermore, to increase their efficiency in operation.

With these and other objects in view the present invention consists in the combination and arrangement of parts, as will be hereinafter more fully described, shown in the accompanying drawings, and particularly pointed out in the appended claim, it being understood that changes in the form, proportion, size, and minor details may be made 15 20 within the scope of the claim without departing from the spirit or sacrificing any of the advantages of the invention.

In the drawings, Figure 1 is a side elevation of a device embodying the features of 25 the present invention, parts being broken away to disclose parts which are otherwise hidden. Fig. 2 is an inverted plan view of the device. Fig. 3 is a cross-sectional view of the device on the line 3 3 of Fig. 1. Fig. 4 30 is a detail perspective view of the device. Fig. 5 is a perspective view illustrating the employment of the present tool as a wire-stretcher.

Like characters of reference designate corresponding parts in all of the figures of the drawings.

The present device includes a central body portion 1, pierced by an eye 2 for the reception of a conventional form of handle 3. The 40 head 4 is integral with the body, and the claw 5 is integral with the other end of the body and is disposed in a general direction at right angles to the body of the head and in substantial parallelism with the handle. The 45 outer side of the claw is of course convexed. The body of the device is provided with a lateral enlargement 6, integral with the eye and located between the latter and the claw, the adjacent faces 7 and 8 of the enlargement 6 50 and the claw 5 being in substantial parallelism for the reception of a nut therebetween, whereby the claw and the enlargement 6 constitute wrench-jaws.

The exposed face of the wrench-jaw 6 is provided with a longitudinal bifurcation 9, 55 which intersects the rear end of the jaw and tapers forwardly therefrom, so as to form a secondary claw in alinement with the main claw 5. Upon each of the members of the secondary claw there is a hooked prong 12, 60 the extremity of which is directed toward the handle and is designed for use in stretching fence-wires, as shown in Fig. 5 of the drawings, wherein has been shown an ordinary fence-post 13 and a fence-wire 14, which 65 may be barbed or smooth, as desired. To stretch the wire, the main claw of the device is placed against the post and the wire is received between the members of the main claw and then wrapped around one of the 70 prongs 12, the handle being held in one hand and the free portion of the wire held in the other hand, whereupon the device is rocked upon its head bearing against the post as a fulcrum, and the wire will thereby be 75 stretched to the desired degree and may then be secured to the post against which the device is engaged. The use of the supplemental claw is illustrated in Fig. 1, wherein a nail has been illustrated by dotted lines as engaged by the claws 5 and 9, so as to be held 80 upon the device in a position to be stuck into a piece of wood preparatory to driving the nail home by striking the same with the head of the tool in the usual manner. Moreover, in drawing the nail it may be started by the main claw 5 and then engaged with the supplemental claw 9, so as to obtain a new hold or purchase thereon, whereby the nail 85 may be entirely withdrawn where it could 90 not be entirely withdrawn by the use of the claw 5 alone.

In one of the outer faces of the jaw 6 there is formed a polygonal socket 10, which intersects the rear edge of the jaw and forms a 95 wrench seat or socket for the reception of a nut of smaller size than can be engaged between the jaw 6 and the claw 5, and another wrench-seat 11 of a different size is formed in the opposite face of the jaw.

Having thus described the invention, what is claimed is—

A tool of the class described comprising a handle, a transverse head upon the handle with one end terminating in a claw, a supplemental claw located between the main claw 105

and the handle, and hooked prongs upon the extremities of the members of the supplemental claw with their ends directed toward the handle, said supplemental claw having 5 shoulders at the base of said prongs for holding wire bights thereon against slipping, for the purpose specified.

In testimony that I claim the foregoing as my own I have hereto affixed my signature in the presence of two witnesses.

JOHN H. LEE.
